UNITED STATES PATENT OFFICE.

SAMUEL ENIS SPENCER, OF SPRINGVILLE, NEW YORK.

AIR-PUMP.

No. 888,762.

Specification of Letters Patent.

Patented May 26, 1908.

Application filed March 1, 1907. Serial No. 360,070.

To all whom it may concern:

Be it known that I, SAMUEL ENIS SPENCER, a citizen of the United States, residing at Springville, in the county of Erie and State of New York, have invented a certain new and useful Improved Air-Pump, of which the following is a specification.

This invention relates to an improved air pump and the object of the invention is to produce a comparatively light but exceedingly strong portable pump for inflating automobile tires or the like, which is mechanically driven and which can be instantly connected to or disconnected from a rotating part on the automobile or the like, such as, for instance, the crank shaft of the engine being manually held in connection with the rotating part through hand grasping parts or handles on the air pump.

The invention also relates to certain details of construction, all of which will be fully and clearly hereinafter described and claimed, reference being had to the accompanying drawings in which,

Figure 1 is a plan view of the improved air pump showing it operatively connected to a rotating shaft, a portion of which is shown in section. Fig. 2 is a central longitudinal section through the improved air pump. Fig. 3 is an enlarged detached inside view of one of the cylinder heads with the inlet valve removed. Fig. 4 is an enlarged detached outside view of one of the cylinder heads with the inlet valve removed and showing a section 35 through the outlet valve on line *a a*, Fig. 1. Fig. 5 is an enlarged central longitudinal section through one of the cylinder heads and a fragment of the cylinder showing the inlet valve. Fig. 6 is an enlarged fragmentary section 40 through the improved pump on line *b b*, Fig. 1 showing the outlet valve. Fig. 7 is an enlarged detached central section through one of the pistons showing the manner of securing it to the piston rod. Fig. 8 is a detached face view of the piston locking disk. Fig. 9 is an enlarged detached end view of 45 one of the pistons, showing a transverse section through the piston rod. Fig. 10 is a detached view of one of the inlet valves.

In referring to the drawings for the details of construction, like numerals designate like parts.

The improved air pump is of the single acting type and primarily consists of a plurality 50 of cylinders, the pistons of which are con-

nected to each other so as to operate in unison, and are given a reciprocating movement by means of a connecting rod and crank on a rotating shaft and it is adapted to be held in temporary engagement with the rotary 60 shaft of an engine by hand grasping handles.

In the preferred adaptation of the invention as illustrated in the accompanying drawings, the cylinders 1 and 2, are formed in opposed relation in a casing 3, the outer 65 ends of the cylinder walls 4 and 5, terminating in annular flanges 6 and 7. The portion of the casing 3, between the cylinders is preferably made slightly larger in diameter than the cylinders, as will be seen by referring to 70 Fig. 2.

Cylinder heads 8 and 9, are fastened by bolts 10, to the flanges 6 and 7, at the outer ends of the cylinders, a packing 11, of leather or other suitable material being interposed 75 therebetween to render the joint air tight, see Figs. 5 and 6.

The pistons, two in number, are constructed substantially as shown in Figs. 2, 7, 8 and 9, and are adjustably fastened to the 80 piston rod, one at each end thereof.

Each piston consists of a flanged metal disk 12, of approximately the same diameter as the cylinder in which it operates, a packing ring 13, of leather or similar material 85 which fits snugly within the cylinder, and a locking disk 14, for fastening the packing ring to the flanged disk and also immovably locking the piston to the piston rod 15.

The flanged disk 12, has an inwardly extending hub 16, which is interiorly screw threaded and into which the end of the piston rod 15, screws.

The packing ring 13, is dished as shown in Fig. 7 being provided with a comparatively wide annular flange 17, and is held against the flat outer face of the flanged disk 12, by the locking disk 14. This disk 14, is of sufficient diameter so as to fit snugly within the flange 17, of the packing ring, and has a 100 square central opening 18, in which the square extremity 19, of the piston rod 15, fits. The locking disk 14, is secured to the flanged disk 12, by two counter sunk screws 20, by which it is drawn up to tightly pinch 105 the packing ring 13, therebetween, see Fig. 7.

It will readily be seen that the square extremity of the piston rod 15, fitting into the square opening in the locking disk absolutely 110

prevents any rotary movement of the piston on the piston rod, and thus rigidly locks the piston in its adjusted position thereon.

To adjust the piston, the locking disk is removed by unscrewing the screws 20, and the flanged disk screwed back or forth until the desired position is reached, when the locking disk is replaced.

The pistons are given a reciprocating movement in the cylinders by means of a rotating shaft 21, journaled in a lateral extension 22, on the casing 3, between the cylinders 1 and 2, and which is connected to the piston rod 15, by a crank 23, and connecting rod 24. The piston rod 15, is bent as shown in Figs. 1 and 2, to provide space for the crank and connecting rod, and is enlarged as shown at 25, in Figs. 2 and 7, near one end to which enlargement one end of the connecting rod 24, is pivoted by a pin 26.

A collar 27, is secured by a pin to the projecting portion of the shaft 21, and prevents any longitudinal movement of the shaft in its bearing, see Figs. 1 and 2.

The casing 3, is cut away in part as shown at 28, to permit the rotation of the crank 23, and also to lighten the construction.

Each of the cylinder heads 8 and 9, is provided with an inlet valve and an outlet valve, the inlet valve being partially located within a central tubular extension 29, on the outside of the cylinder head, and the outlet valve being located in a vertical enlargement 29^a.

A longitudinal central opening 30, is formed in the cylinder head around which are grouped a plurality of inlet ports 31. These ports 31, lead into the cylinders from the interior of the tubular extension 28. An annular flange 32, is formed on the inner face of the cylinder head, being smaller in diameter than the cylinder into which it projects, but larger than the group of inlet ports 31, see Fig. 3. A ring 33, of leather or other suitable material fits snugly against the cylinder head within the flange 32, and surrounds the inlet ports 31. This ring 33, forms a valve seat for a disk valve 34, the stem 35, of which projects through the central opening 30, into the tubular extension 29. The projecting portion of the valve stem 35, is encircled by a coil spring 36, which is held in place by a washer 37, see Fig. 5. This constitutes the inlet valve.

The outlet valve is of the ball type and is illustrated in Figs. 4 and 6.

The enlargement 29^a, has a deep vertical chamber 38, which communicates with the cylinder by means of a passage or outlet port 39. A ring of leather or similar material 40, is placed in the bottom of the chamber 38, and has a central opening which registers with the outlet port 39. This leather ring constitutes a valve seat for a ball valve 41, which is adapted to seat in, and normally close the central opening, see Figs. 4 and 6.

The ring 40, is held in place by a tubular retaining plug 42, which is screwed into the chamber 38, in the manner shown. This tubular retaining plug has an interior annular flange 43, at its lower end, the upper surface of which is beveled so as to lead the ball valve 41, back into its seat. A transverse bar 44, limits the upward movement of the ball.

The two valve chambers 38, are connected by a longitudinal tube 45, which has its ends seated in the flanges 6 and 7. A passage 46, in each cylinder head registers with the tube and connects the tube with the valve chamber in the manner shown in Fig. 6. It will be noticed by referring to said figure that the extremity of the tube 45, projects beyond the flange so that it embeds itself in the packing 11, and prevents any leakage of air at this joint. The upper end of the valve chamber 38, is closed by a screw plug 47, see Figs. 4 and 6.

As the valves on both cylinders head are similar, but one set has been described, like reference numerals being used to indicate corresponding or like parts on both sets.

A nipple 48, screws transversely into one of the enlargements 29^a, and communicates with the chamber 38. A rubber tube 49, may be secured to this nipple by a coupling 50, to convey the compressed air to any desired place, such as, for instance, the pneumatic tire of an automobile.

A pressure gage 51, of any well known kind may be attached to the pump by screwing its stem into the vertical opening 52, in one of the screw plugs 47, to indicate the pressure of the compressed air.

The tubular extensions 29, on the cylinder heads 8 and 9, are interiorly screw threaded and a pair of hollow handles 53, open at the ends, are screwed into the extensions as shown in Figs. 1 and 2. These handles form convenient means for holding the pump and being hollow also serve as inlet passages to conduct air to the inlet valve chambers.

The outer extremity of the shaft 21, is made square in cross section and is adapted to be inserted in a square opening 54, in the end of a rotating element, such as the crank shaft 55, of an engine. By this means the shaft of the pump is connected directly and positively to the engine shaft and revolves in unison with it.

The operation of the improved air pump is as follows:—When it is desired to inflate the tires of an automobile or the like, the end of the rubber tube 49, is first coupled to the tire valve in the usual manner. The operator now grasps the pump by the handles 53, and inserts the square end of the shaft 21, into the square opening 54, in the end of the engine shaft 55, in the manner shown in Fig. 1. This causes the shaft 21, to revolve and reciprocate the pistons in

the cylinders 1 and 2. The air as it is compressed within the cylinders is conveyed by the outlet ports or passages 39, into the valve chambers 38. The air in one of the 5 valve chambers 38, is conducted to the other chamber which has the nipple 48, attached thereto, by the tube 45, so that all the air compressed within the cylinders centers in that chamber and is conveyed to the automobile tire through the nipple 48, and the rubber tube. When the pressure gage 51, registers the desired pressure within the tire, the operator withdraws the shaft 21, from the rotating engine shaft which stops the 10 pump.

This improved pump is entirely separate and distinct from the automobile and is supported wholly by hand not being connected or attached to any portion of the 20 automobile except the shaft of the engine and only to said shaft for the purpose of transmitting power.

I claim as my invention:

1. The combination with an engine and its 25 shaft, of a pump comprising a plurality of cylinders, pistons in said cylinders, a shaft having crank connection with said pistons, means for temporarily connecting said shaft to the engine shaft and handles attached to 30 the pump and adapted to be gripped by the operator to hold the pump shaft in temporarily operative engagement with the engine shaft.

2. The combination with an engine and its 35 shaft, of a pump comprising a plurality of cylinders, pistons in said cylinders, a shaft having crank connection with said pistons, means for temporarily connecting said shaft to the engine shaft and means attached to 40 the pump and adapted to be grasped by the operator to wholly support the pump and hold the pump shaft in temporarily operative engagement with the engine shaft.

3. The combination with an engine and its

shaft, of an air pump adapted to be temporarily attached to said engine to be driven therefrom comprising a hollow casing having a cylinder at each end, a cylinder head attached to the outer end of each cylinder, an outlet valve and inlet valve in each cylinder head, a tube connecting the outlet valves, a connection extending from said tube to the part requiring a compressed medium, pistons in said cylinders, a shaft, a crank extending from said shaft, a connection between said crank and one of the pistons and oppositely extending handles on the cylinder heads adapted to be grasped by the operator to wholly support and hold the air pump in position to be driven from the engine with 45 the shaft of the air pump connected to the engine shaft, substantially as set forth.

4. The combination with an engine and its shaft, of a pump having a cylinder and a piston in said cylinder, a shaft having crank connection with said piston, means for temporarily connecting said shaft to the engine shaft and means attached to the pump and adapted to be grasped by the operator to wholly support the pump and hold the pump shaft 50 in temporarily active engagement with the engine shaft.

5. A device of the class described comprising a hollow casing having a cylinder at each end, a cylinder head attached to the outer 55 end of each cylinder and having a tubular extension forming both an air inlet and a handle adapted to be grasped by the hands of the operator to hold the device in position to be driven, pistons in said cylinders, a shaft, a 60 crank extending from said shaft and a connection between said crank and one of the pistons.

SAMUEL ENIS SPENCER.
